UNITED STATES PATENT OFFICE.

JOHN C. KLEIN, OF PITTSBURG, PENNSYLVANIA.

IMPROVEMENT IN ROLLS FOR ROLLING WEDGES.

Specification forming part of Letters Patent No. 146,598, dated January 20, 1874; application filed May 2, 1872.

To all whom it may concern:

Be it known that I, JOHN C. KLEIN, of Pittsburgh, in the county of Allegheny and State of Pennsylvania, have invented certain new and useful Improvements in Machinery for Rolling Wedges, &c., of which the following is a specification:

My invention relates more particularly to the manufacture of wedges, crow-bars, and similar implements, by means of oscillating rolls.

The object of the first part of my invention is to provide means for intermitting the operation of the rolls, when it is desired to stop the machine in order to give the attendant time to insert a new blank or to adjust the dies; and the improvement consists in combining oscillating rolls and a continuously-revolving shaft with a connecting-rod provided with hinged links and pivoted levers, in such manner that the connecting-rod may be thrown into or out of gear with the driving-shaft, and impart motion to the rolls either continuously or intermittently, as hereinafter described.

The object of the next part of my invention is to provide an improved mode of securing the dies to the rolls, so as to form blanks with tapering sides and to be capable of adjustment for different inclinations; and the improvement consists in combining a roll having a socket with a projecting or inclined side, a die with a correspondingly formed side to fit the socket, a key for securing the die to the roll, and a liner for adjusting the die eccentrically to the roll, as hereinafter described.

The object of the next part of my invention is to provide improved dies for rolling tapers, which consists in dies formed with converging ridges, which ridges bite the iron and draw it in to the rolls, thus facilitating the operation, and also form grooves in the wedge, which prevent the wedge from being too easily withdrawn from its work.

In the accompanying drawings, Figure 1 is a perspective view, showing the general construction of my improved machine, with the connecting-rod in position for arresting the movement of the rolls when the dies are toward the front of the machine. Fig. 2 is an enlarged view of the connecting-rod detached,

with its parts in position for imparting a continuous movement to the rolls; Fig. 3, a similar view of the same, with its parts in position to stop the rolls instantaneously at any part of their travel; Fig. 4, a similar view of the same, with its parts in position for arresting the movement of the rolls when the dies are turned toward the rear of the machine; Fig. 5, a front elevation of the machine, with the dies turned toward the front; Fig. 6, a transverse section through the rolls in the line *w w* of Fig. 5, enlarged to show the manner of adjusting and securing the dies to the rolls; Fig. 7, a cross-section of one of the dies at right angles to Fig. 6; Fig. 8, a transverse section through the rolls in the line *x x* of Fig. 5, showing the dies for forming wedges, and also the device for preventing the blank from passing too far between the dies; Fig. 9, a perspective view of a blank after having passed through the dies shown in Fig. 6; and Fig. 10, a perspective view of a wedge when completed. Fig. 11 is an enlarged front view of one of the dies, showing the raised ridges.

A bed-plate, A, of suitable form, has pillow-blocks B B bolted to it, which support a driving-shaft, C, that is revolved continuously by the prime mover. Housings D D are also secured to the bed-plate and receive bearings which support the journals of a pair of rolls, E E', in the usual way. To one of the journals of each of the rolls are secured segment-gears F F', which mesh with each other and are operated by a connecting-rod, G, from the driving-shaft to communicate an oscillating movement to the rolls. The connecting-rod G is journaled to a wrist-pin, f, on the lower segment-gear F', and near its opposite end is slotted to receive the wrist-pin e of a crank, C', on the driving-shaft C. Links g g', slightly recessed at their free ends, are pivoted to the connecting-rod at the extremities of the slot in which the wrist-pin works and through which it protrudes, so that when their free ends are raised, as presently to be described, they form a bearing for the wrist-pin. Foot-levers H H' are pivoted to the bed-plate adjacent to the housings, and are provided with spring-arms h h', which extend back to such a distance that when the treadle ends of the foot-levers H H' are depressed, the spring-

arms will bear against the links g g' and press them up against the top of the slot in the connecting-rod G , in which position the wrist-pin c will be in gear with the connecting-rod, and motion will be imparted continuously to the rolls. (See Fig. 2.)

When, on the other hand, the foot-levers are left free, the spring-arms and links will drop of their own gravity, and the wrist-pin c will travel in the slot without imparting motion to the rolls. (See Fig. 3.) When the foot-lever H is depressed, and the links g consequently elevated, the rolls will be brought in the proper position for feeding the blank to the dies, and there arrested, (see Fig. 1;) but if it is desired to arrest the rolls at the opposite extremity of their travel, they will be brought to and arrested in that position by depressing the foot-lever H' , and consequently elevating the link g' , as seen in Fig. 4.

In order to roll tapering blanks for crow-bars and other purposes, I provide dies I I' , grooved concentrically with the rolls, and secured therein to suit the desired taper of the blanks, as follows: A recess or socket having one of its sides inclined, as seen in Fig. 7, is formed in the roll, into which the die having a correspondingly-inclined side is inserted, and one of its ends is elevated, so as to give it more or less eccentricity with the roll, to suit the taper of the blank required, by inserting beneath it a liner, i^1 , having a projecting head or flange, i^2 . A key, i^3 , is inserted between the head of the liner and the opposite side of the groove of the roll, and, when driven home, holds the die firmly in position for its work.

By using liners of different thicknesses, blanks of correspondingly-different tapers may be formed.

By means of these dies, a rectangular blank can be partially tapered, as shown in Fig. 9, and the metal at the same time prevented from spreading laterally at the tapering end of the blank by the flanges on the sides of the die that form the walls of the groove.

In order to complete and finish the crow-bars or wedges by the rolling operation, I provide dies K K' , secured in recesses in the rolls, and having grooves formed therein eccentrically to the rolls that taper to the surface of the dies, so that the iron can be rolled to an edge.

It will be readily seen that, if a rectangular bar were passed between the dies K K' , the metal would be spread laterally at that part

of the die where the groove terminates, as it would have no flanges or side walls to confine it in that direction, and would consequently form a wedge that would be wider at its edge than at the butt or larger end. This I obviate by first passing the rectangular blank between the dies I I' , which tapers the blank and reduces the bulk of metal at the smaller end of the wedge to such an extent that, when turned a half-turn and passed between the dies K K' , the blank will be formed into a wedge having parallel sides or edges.

In order to cause the dies to take hold more firmly upon the wedge-blank, as well as to form depressions in the finished wedge, which will enable it to be used with greater efficiency, the dies are provided with a series of converging ridges, K^2 , and also a longitudinal ridge, which further facilitates these objects.

To prevent the blank from being inserted too far between the dies in the operation of rolling, I provide tongs L , having stops l l' formed upon their gripping ends, which abut against the ends of the dies, and prevent the blank from being inserted too far between the dies.

By means of the improved connecting-rod, which permits the rolls to be stopped at pleasure, I am enabled to manipulate the work more completely. The dies can be readily removed, replaced, and adjusted; and the improved method and devices herein described enable me to form and finish a wedge entirely by the operation of rolling.

I claim as my invention and desire to secure by Letters Patent—

1. The combination of oscillating rolls, a continuously-revolving driving-shaft, and a connecting-rod provided with hinged links and pivoted levers, these parts being combined to operate for intermitting the operation of the rolls, substantially as set forth.

2. The combination of a roll having a recess with a projecting side, a die having a correspondingly-formed side to fit the recess, a liner for adjusting the eccentricity of the die, and a key to secure the die to the roll, substantially as and for the purpose set forth.

3. The die provided with converging ridges, to form a wedge with depressions corresponding to the ridges, substantially as set forth.

JOHN CHR. KLEIN.
